US0D1060222S

(12) **United States Design Patent** (10) **Patent No.:** **US D1,060,222 S**
(45) **Date of Patent:** **** Feb. 4, 2025**

(54) **BATTERY CHARGER**

(71) Applicant: **HUSQVARNA AB**, Huskvarna (SE)

(72) Inventors: **Gustav Landberg**, Trosa (SE); **Tor Sigurdson**, Stockholm (SE); **Patrik Almqvist**, Stockholm (SE)

(73) Assignee: **HUSQVARNA AB**, Huskvarna (SE)

(**) Term: **15 Years**

(21) Appl. No.: **29/808,006**

(22) Filed: **Sep. 16, 2021**

(30) **Foreign Application Priority Data**

Mar. 18, 2021 (EM) 008465520-0002

(51) **LOC (15) Cl.** **13-02**

(52) **U.S. Cl.**

USPC **D13/107**

(58) **Field of Classification Search**

USPC D13/103, 107, 108, 109, 110, 117, 118, D13/119, 120, 122, 184, 199, 123, 124, D13/158, 160, 162, 164; D14/101, 251, D14/253, 432, 434

CPC H02J 7/00; H02J 7/0042; H02J 7/0044; H02J 7/045; G06F 1/26; G05F 1/00; G05F 1/10; H01M 10/623

(57) **CLAIM**

The ornamental design for a battery charger as shown and described.

DESCRIPTION

The patent or application file contains a least one drawing executed in color. Copies of this patent or patent application publication with color drawing(s) will be provided by the Office upon request and payment of the necessary fee.

FIG. 1 is a perspective view of a battery charger of the present invention;

FIG. 2 is a front view of the battery charger of FIG. 1;

FIG. 3 is a rear view of the battery charger of FIG. 1;

FIG. 4 is a left side view of the battery charger of FIG. 1;

FIG. 5 is a right side view of the battery charger of FIG. 1;

FIG. 6 is a top view of the battery charger of FIG. 1; and,

FIG. 7 is a bottom view of the battery charger of FIG. 1.

1 Claim, 7 Drawing Sheets
